CLAIM

The ornamental design for a power inverter as shown and described.

DESCRIPTION

FIG. 1 is a front, right and top perspective view of a power inverter showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an enlarged view of a portion labeled as "9" on FIG. 1.

The long dash-short dash broken lines depict enlargement boundaries that form no part of the claim. The evenly broken lines illustrate portions of the Power Inverter that form no part of the claimed design.
